GARDEN AND WALK LIGHT

Mitchell Bobrick, Pacific Palisades, Calif., assignor to
Avis Industrial Corporation, Madison Heights, Mich.,
a corporation of Delaware

Filed Apr. 7, 1967, Ser. No. 6,583

Term of patent 14 years

(Cl. D48—31)

FIG. 1.

FIG. 2.

FIG. 3.

FIG. 6.

FIG. 4.

FIG. 5.

FIG. 7.

FIG. 8.

FIG. 10.

FIG. 9.

FIG. 12.

FIG. 1 is a side elevational view of one embodiment of the light;

FIG. 2 is a front elevational view;

FIG. 3 is a rear elevational view;

FIG. 4 is a top plan view;

FIG. 5 is a bottom plan view;

FIG. 6 is a side elevational view similar to FIG. 1, but with the light adjusted to a different position;

FIG. 7 is a side elevational view of another embodiment of the light;

FIG. 8 is a top plan view;

FIG. 9 is a bottom plan view;

FIG. 10 is a front elevational view;

FIG. 11 is a rear elevational view; and

FIG. 12 is a side elevational view similar to FIG. 7, but with the light adjusted to a different position.

I claim:

The ornamental design for a garden and walk light, as shown and described.
